BALL CRANK ENGINE

Thompson M. Berry, Shaw, Miss., assignor of
twenty-five per cent to Christopher R. Berry,
Benton, Miss.

Application September 30, 1935, Serial No. 42,938

3 Claims. (Cl. 74—57)

This invention relates to engines and has for an object to provide novel means for translating the rectilinear movement of the pistons to rotary movement of the engine shaft without the use 5 of the conventional crank movement.

It has been known for this purpose to mount on the shaft to be rotated a wobble plate operated by the pistons and engaging a pair of circular cam members mounted on the shaft and 10 having their adjacent faces arranged obliquely and spaced apart parallel with one another to provide an oblique cam groove between the members to receive the wobble plate. However, no attempt has hitherto been made to provide 15 guides for the pivotal connections between the piston rods and the wobble plate to resist any tendency of these connections to twist and accordingly an object of this invention is to provide a housing for the circular cam members and 20 wobble plate, the housing having guide slots which are operatively connected with the connections between the connecting rods and the wobble plate to permanently restrain said connections to rectilinear movement.

25 A further objection to the above described type of motion translating mechanism is that it is difficult to obtain efficient coaction between the wobble plate and the pistons or connecting rods owing to the peculiar movement of the wobble plate and accordingly the present invention has for another object to provide arcuate 30 connecting rods which permit of the bearings on the wobble plate being made much shorter than ordinarily and hence less liable to be disrupted due to torsional strains.

35 A further object of the invention is to provide a device of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming part 50 of this specification,

Figure 1 is a longitudinal sectional view through an internal combustion engine constructed in accordance with the invention.

Figure 2 is a cross section taken on the line 2—2 of Figure 1 and showing the wobble plate in 5 elevation.

Figure 3 is an enlarged detail section of the motion translating parts shown in Figure 1 with parts in elevation.

Figure 4 is a cross section taken on the line 10 4—4 of Figure 1.

Figure 5 is a side elevation of the housing for the motion translating parts and showing the guide slots.

Figure 6 is a cross sectional view taken on the 15 line 6—6 of Figure 5.

Figure 7 is an exploded detail elevation of the engine shaft and ball rotating members.

Referring now to the drawings in which like characters of reference designate similar parts 20 in the various views, 10 designates a plurality of internal combustion engine cylinders which are arranged in opposed relation around the engine shaft 11. A half ball member 12 is formed integral with the shaft and a half ball 25 member 13 is keyed to the shaft, as shown at 14 in Figures 3 and 7. The opposed faces of the ball members are arranged obliquely and spaced apart parallel with one another to provide an oblique cam groove 15 between the members. 30 One of the members is provided with an oblique hub 16 perpendicular with its oblique face, against which the oblique face of the other member is held in abutting contact by means of a jam nut 17 which is screwed on to a threaded 35 portion 18 of the shaft.

40 Mounted on the hub 16 between the members 12 and 13 is a ring 19 and annular series of ball thrust bearings 20 are provided between the sides of the ring and the oblique faces of the ball members to reduce friction between the parts. Thus the ball members 12 and 13 can 45 rotate easily relative to the ring 19 when the ring is oscillated by the pistons as will presently be described.

The ring is provided with radially disposed pins 21, one for each cylinder, as best shown in Figure 2, and loosely mounted on each pin is a sleeve 22 having ears 23 at diametrically opposite points thereof. The sleeve is confined against a shoul-

der 24 on the pin by means of a washer 25 and a nut 26. Pivot to the ears 23 of each sleeve are the arcuate connecting rods 27 of opposing pistons 28. Each piston is provided with a substantially triangular web 29 which extends slightly beyond the open end of the cylinder and is pivoted to the associated connecting rod. Thus the connecting rods can swing relatively to the piston and the associated sleeve 22 can swivel on the pin 21 during reciprocatory movement of the pistons.

When the connecting rods 27 are reciprocated they tend to oscillate the ring 19 and give it a wobbling motion, whereby the axis of the ring 15 prescribes two opposite cones having their apices meeting at the center of the ring 14. The ring 19 in being confined in the cam groove 15 between the ball members 12 and 13 will impart a rotary movement to the members thus rotating the 20 shaft 11.

The pins 21 are subjected to considerable torsional strain and to reinforce them to resist this strain a housing 30, best shown in Figure 5, is preferably formed of two mating sections 31 25 and 32 which are provided with flanges 33 at intervals through which bolts 34 are passed to assemble the sections upon the ball members 12 and 13. A plurality of slots 35 are formed in the housing parallel with the engine shaft 11, these 30 slots corresponding in number to the number of pins 21 on the ring 19 and receiving the pins as best shown in Figure 3. The walls of the slots form guides for confining the pins to rectilinear movement and also reinforce the pins to resist 35 torsional strains.

The housing 30 is provided at diametrically opposite points with tubular bearing housings 36 which extend along the engine shaft 11 and are equipped with ball bearings 37 for journaling the 40 engine shaft 11. As shown in Figure 4, the bearing housings are provided with lugs 38 which are bolted as shown at 39 to heads 40 to which the open ends of the cylinders are bolted as shown at 41. The heads 40 are provided with flanges 45 42 which are bolted together, as shown at 43 in Figure 1 and form a casing or housing for the reciprocating rods 27 and associated parts.

It will be observed that the pins 22 are relatively short in length, this being made possible 50 by the curvature of the connecting rods 27 and the elongated webs 29 which connect the rods to their respective pistons adjacent the wall of the pistons. These short bearings or pins 22 are less liable to be disrupted due to torsional strains produced by the peculiar movement of the ring 19 or wobble plate, than where long pins are used and especially where long pins are used without reinforcing and guiding means such as the above described housing 30 with the guide slots 35 55 therein.

From the above description it is thought that the construction and operation of the invention will be fully understood without further explanation.

60 65 What is claimed is:

1. An internal combustion engine comprising cylinders, pistons in the cylinders, an engine shaft parallel with the cylinders, a ball on the shaft including two half ball members having their circular plane faces confronting each other and being disposed obliquely across the shaft, one of the members being integral with the shaft and having a shoulder normal to its plane face, the other member being keyed to the shaft and having a portion of its plane face abutting the shoulder, a nut adjustably securing the keyed member to the shaft, the shoulder and the plane faces of the ball members forming an oblique cam groove, a ring in the cam groove having radial short pins on the periphery, curved connecting rods for the cylinders, sleeves loose on the pins and pivotally connected to the connecting rods, and a housing for the ball having guide slots parallel with the engine shaft and receiving the pins outside of the sleeves.

cylinders, pistons in the cylinders, an engine shaft parallel with the cylinders, a ball on the shaft including two half ball members having their circular plane faces confronting each other and being disposed obliquely across the shaft, one of the members being integral with the shaft and having a shoulder normal to its plane face, the other member being keyed to the shaft and having a portion of its plane face abutting the shoulder, a nut adjustably securing the keyed member to the shaft, the shoulder and the plane faces of the ball members forming an oblique cam groove, a ring in the cam groove having radial short pins on the periphery, curved connecting rods for the cylinders, sleeves loose on the pins and pivotally connected to the connecting rods, and a housing for the ball having guide slots parallel with the engine shaft and receiving the pins outside of the sleeves.

2. An internal combustion engine, cylinders, pistons in the cylinders, an engine shaft parallel with the cylinders, a ball on the shaft including two half ball members having their circular plane faces confronting each other and being disposed obliquely across the shaft, one of the members being integral with the shaft and having a shoulder normal to its plane face, the other member being keyed to the shaft and having a portion of its plane face abutting the shoulder, a nut adjustably securing the keyed member to the shaft, the shoulder and the plane faces of the ball members forming an oblique cam groove, said ball having an oblique hub forming the bottom of the groove, a ring in the cam groove seated on the hub and having radially disposed short pins on the periphery, curved connecting rods for the cylinders, sleeves loose on the pins and pivotally connected to the connecting rods, and a housing enclosing the ball and having straight guide slots parallel with the engine shaft and receiving the pins outside of the sleeves.

3. An internal combustion engine comprising cylinders, pistons in the cylinders, an engine shaft parallel with the cylinders, a ball on the shaft including two half ball members having their circular plane faces confronting each other and being disposed obliquely across the shaft, one of the members being integral with the shaft and having a shoulder normal to its plane face, the other member being keyed to the shaft and having a portion of its plane face abutting the shoulder, a nut adjustably securing the keyed member to the shaft, the shoulder and the plane faces of the ball members forming an oblique cam groove, a ring in the cam groove having radially disposed short pins on the periphery, annular series of ball bearings between the ring and the walls of the cam slot, a housing encircling the ball and having slots parallel with the engine shaft and receiving the pins outside of the sleeve, tubular bearing housings integral with the first named housing and extending along the engine shaft, and annular series of ball bearings in the tubular housings journaling the engine shaft.
